by the Secretary of War

Application March 29, 1946, Serial No. 657,950

5 Claims. (Cl. 250—33.67)

1

This invention relates to antennas for high frequency radio and radar systems and more particularly to an antenna for radiation or reception of horizontally or vertically polarized waves.

In antennas as hereinbefore known including those utilizing dipoles and single loops as radiating elements a common disadvantage is that there is too much response to signals of unwanted polarization. In other words, they have insufficient discrimination between vertically and horizontally polarized waves. It has been found that this disadvantage may be considerably overcome by a dual loop antenna according to this invention wherein two loops are connected in parallel and in phase opposition. The pattern of the "bucking" dual loop arrangement of the present invention is like two adjacent spheres with little or no response from the sides between these spheres. The response of the antenna according to the invention is to horizontal polarization when the common plane of the two loops is horizontal. Similarly when the plane of the dual loop is in the vertical position, the maximum response would be to vertical polarization.

Accordingly, it is one of the objects of the present invention to provide an antenna having maximum response to energy polarized parallel to the plane of the radiating elements of the antenna.

Another object of the invention is to provide an antenna having maximum response to horizontally polarized waves of electromagnetic energy and which has a high discrimination against vertical polarization.

Still another object is to provide a dual loop antenna in which the two loops are connected in phase opposition.

It is still another object of the invention to provide a direction finder antenna for the reception of horizontally polarized waves.

For a better understanding of the invention together with other and further objects thereof, reference is had to the following description, taken in connection with the accompanying drawing, in which:

Fig. 1 is a diagrammatic top view of an antenna showing the instantaneous current relations and the approximate radiation patterns produced thereby;

Fig. 2 is a horizontal sectional view of the antenna as constructed according to a modification of the invention;

Fig. 3 is a completed sectional view along the line 3—3 of Fig. 2; and

Fig. 4 is a completed sectional view along the line 4—4 of Fig. 2.

Referring to Fig. 1 there is shown an antenna

10 comprising two adjacent loops 11 and 12 lying in substantially the same plane. The terminals 13 and 14 may connect to a balanced transmission line (not shown). With this arrangement, 5 the arrows indicate the direction of the current distribution, the broken lines indicating the two lobed radiation pattern produced.

In the modification shown in Figs. 2, 3 and 4, the antenna 20 is generally formed by two substantially E-shaped sections 21 and 22 facing each other with the center branches 23 and 24 being connected and with the adjacent end branches 25 and 26 of section 21, and 27 and 28 of section 22 being slightly spaced apart at P and Q thereby in effect forming two adjacent loops 29 and 30 interrupted at P and Q. The end branches 25, 26, 27 and 28 may be rounded or curved so that these branches give the antenna 20 a generally O-shaped or oval-shaped appearance from above. Section 21 is in the form of a "single wire" conductor which may be either a solid or hollow conductor while section 22 is in the form of a coaxial conductor having inner conductor sections 25', 27' and 28' and outer concentric conductor sections 24', 27'' and 28''. The free ends of inner conductor sections 27' and 28' extend beyond the outer conductor sections 27'' and 28'' and connect to the ends of sections 25 and 26 of section 21 at P and Q, respectively, thus 15 completing electrical connection through the loops 29 and 30. Thus, the loop 29 comprises branches or sections 24, 27, 25 and 23 while loop 30 comprises branches or sections 24, 28, 26 and 23, the centerline C as shown in Fig. 2 passing 20 through the junctions of the two loops.

Energy is fed to or coupled from the loops 29 and 30 preferably by means of a coaxial conductor transmission line 32 having an inner conductor 33 and an outer concentric conductor 34 (Fig. 40 3). Since at low frequencies the loops are almost entirely inductive, increased sensitivity may be obtained by resonating the loops, that is, by tuning out the inductance reactance at the point T₁ or at some point in inner conductor member 45 24'. The loops may be supported by a metal column or by transmission line 32 connected at point R which is located at the point of electrical symmetry of the loops so that the impedance of the path between P and R via member 25 is the same 50 as for the path between P and R via member 27. As shown in Fig. 3, center conductor 33 is connected to center conductor 24' and outer conductor 34 is connected to outer conductor section 24'' and to center branch or section 23 of section 21, the connections being indicated in Fig. 2 by T₁ and T₂, respectively. It will be understood that while the external connections are 55

made at T_1 and T_2 , the loops 29 and 30 are connected to the transmission lines at point P and Q, the instantaneous current distribution being indicated by the arrows. As the point R is located at the point of electrical symmetry and the connections to transmission line 32 are at point R with transmission line 32 mounted substantially perpendicularly to the plane of loops 29 and 30 at the point R, the coupling to loops 29 and 30 is made in a symmetrical manner without disturbing the current distribution.

With the two loops 29 and 30 of Figs. 2, 3 and 4 or of the loops 11 and 12 of Fig. 1 being connected in phase opposition, the two lobed pattern indicated in Fig. 1 is produced. When the planes of the two loops are horizontal, there is maximum response to horizontally polarized waves and a high discrimination against vertically polarized waves, and similarly when the plane of the loops is vertical the antenna possesses high discrimination against horizontally polarized waves with maximum response to vertically polarized waves. Thus, the antenna according to this invention may be utilized as a direction finder antenna or as a beacon in association with radio object-locating systems.

It has been found that overall loop dimensions E and D (Fig. 2) of 16 and 13 inches respectively are satisfactory for operation as a direction-finding antenna in the frequency range of 100 to 300 megacycles (per second) when the loops are resonated. A satisfactory outer diameter of the loop sections 25, 26, 27 and 28 is about 1.5 inches.

While there has been described what is at present considered the preferred embodiment of the invention, it will be obvious to those skilled in the art that various changes and modifications may be made therein without departing from the invention.

What is claimed is:

1. An antenna comprising two substantially E-shaped sections facing each other with the center branches thereof joined to effectively form two balanced symmetrically connected loops lying in the same plane, one of said E-shaped sections comprising a single wire conductor, the other of said sections comprising a coaxial conductor having an inner conductor and an outer concentric conductor, the ends of the free end branches of said single wire conductor being slightly spaced from the adjacent ends of said outer conductor, the ends of said inner conductor extending beyond said outer conductor and connected to the adjacent ends of said single wire conductor to complete each of said loops, means for transmitting electromagnetic energy to and from said loops, said means being coupled at the point of electrical symmetry of said two loops whereby said current flowing in one of said loops is in phase opposition to that in the other loop, said antenna thereby having maximum response to energy polarized in the plane parallel to the common plane of said loops and possessing high discrimination against energy polarized in the plane perpendicular to that of said loops.

2. An antenna as claimed in claim 1 wherein said transmitting means comprises a coaxial transmission line mounted perpendicularly and connected to the center branch of said loops at the point of electrical symmetry of said loops, the inner and outer conductors of said coaxial transmission line being connected to the inner and outer conductors respectively of the center branch of said coaxial section.

3. An antenna for translating electromagnetic

5
10

energy polarized in a single plane comprising two similar, co-planar conductors forming loops connected in parallel with each other, said conductors being disposed as mirror-images of each other, transmission line means coupled to the portions of each of said conductors which are spaced furthest from one another for feeding electromagnetic energy to each of said conductors, and means including said transmission line means for causing current to flow clockwise around one loop and counter-clockwise around the other loop.

4. An antenna for translating electromagnetic energy polarized in a single plane comprising two similar, co-planar conductors forming loops connected in parallel with each other, said loops being disposed as mirror-images of each other, each loop comprising a first portion consisting of a coaxial line and a second portion consisting of a single conductor, said single conductor being connected at one end to the inner conductor of said line at the end of said line adjacent said one end, and said single conductor being connected at its other end to the outer conductor of said line at the end of said line adjacent said other end of said single conductor, and means coupled between the inner and outer conductor of each line near the portion thereof where its outer conductor is connected to said single conductor for supplying electromagnetic energy to said antenna.

5. An antenna for translating electromagnetic energy polarized in a single plane comprising two similar, co-planar conductors forming loops connected in parallel with each other, said loops being disposed as mirror-images of each other and each loop consisting of symmetrical halves, one of said halves of each loop consisting of a coaxial line and the other of said halves consisting of a single conductor having substantially the same diameter as that of the outer conductor of said line, said single conductor being connected at one end to the inner conductor of said line at the end of said line nearest said one end, and said single conductor being connected at its other end to the outer conductor of said line at the end of said line nearest said other end of said single conductor, the portions of said loops where said center conductor is connected to said single conductor being substantially the furthest spaced portions of said antenna, and means coupled between the inner and outer conductors of each line near the portion thereof where its outer conductor joins said single conductor for supplying electromagnetic energy to said antenna.
